UNITED STATES PATENT OFFICE.

CHRISTOPH J. MICHELS, OF PORT WASHINGTON, WISCONSIN, ASSIGNOR TO GILSON MANUFACTURING COMPANY, A CORPORATION OF WISCONSIN.

CORE-MAKING MACHINE.

1,282,099.

Specification of Letters Patent. Patented Oct. 22, 1918.

Application filed January 18, 1918. Serial No. 212,520.

To all whom it may concern:

Be it known that I, CHRISTOPH J. MICHELS, a citizen of the United States, residing at Port Washington, in the county of

5 Ozaukee and State of Wisconsin, have invented new and useful Improvements in Core-Making Machines, of which the following is a specification.

This invention relates to core making machines; and the objects in view are to produce a comparatively simple and inexpensive machine for this purpose which after being started by hand will automatically complete its operation of forming the core.

15 Other objects and advantages of the invention will hereinafter appear, and the novel features thereof will be more particularly pointed out in the appended claims.

Referring to the drawings:

20 Figure 1 is a side elevation of a core making machine embodying my invention, the parts being shown in their inoperative position as before the machine is started;

25 Fig. 2 is a similar view of the machine, the parts being shown in the position they occupy after the machine has been started and the sand-hopper has reached the rear end of the core-plate and its discharge closed;

30 Fig. 3 is a front elevation of the machine, the parts being shown as in Fig. 1;

Fig. 4 is a fragmentary sectional view taken on the line 4—4 of Fig. 6;

35 Fig. 5 is a fragmentary side elevation, the view being taken at the opposite side of the machine shown in Figs. 1 and 2; and

Fig. 6 is a top plan view, the parts being in the position shown in Fig. 1.

Similar numerals of reference indicate 40 similar parts throughout the several figures of the drawings.

In order to support the mechanism hereinafter described, I employ a pair of oppositely located side-frames 1, the same being 45 suitably braced and secured together as is customary in such cases. From their longitudinal middles, these side frames extend preferably on divergent lines for a portion of their lengths, as at 1^a, beyond which they

again extend parallel to each other, as at 1^b, 50 these latter portions, as will hereinafter appear, forming supports for bearings that carry the driving mechanism.

The rear parallel portions of the frames 1, support the core-plate 4, the same having 55 the usual molds or cores 2, which, of course, vary as to shape in accordance with the character of the core it is desired to form. This plate is removably supported and secured upon the frames in any desired manner, in the present instance by companion hinge-members 3, the same being separable and connected pivotally together by removable pintles. In this manner core-plates 60 having other shaped openings or molds may 65 be substituted for that shown, or, if any plate is to be continuously used, after forming the core, the plate may be swung upward for conveniently removing the cores.

Extending forwardly from the rear parallel portions of the sides 1, and with their upper edges in the same plane as the upper surface of the core-plate is an extension or table 5, the same being situated between the diverging portions 1^a of the frames or sides, 75 such extension therefore forming a continuation of the upper surface of the core-plate.

At one side of the machine, at its front, is located a bearing-frame 7, and upon the upper end of the same and at corresponding 80 points upon each of the sides 1, are located transversely alining bearings 9, in which is located a drive-shaft 10, carrying spur-gears 11 and 12, which are fast upon and therefore move with the shaft.

Similar bearings 8, are located on the bearing-frame 7 and the adjacent side-frame 1, and in such bearings is journaled a shorter counter-shaft 13. This shaft carries pulleys 14 and 15, and between the same 90 small spur-gears 16 and 17, the former meshing with the spur-gear 11, and the latter with the spur-gear 12, and therefore adapted to drive the same in accordance with the direction of rotation of said counter-shaft and 95 as will be hereinafter explained. The adjacent ends of the hubs of the small gears 16 and 17 are toothed, as at 16^a and 17^a, re-

spectively, while the opposite ends of the hubs constitute the male members 18, of friction-clutches, the opposite companion or female members, 19, being formed in the 5 sides of the pulleys 14 and 15. The pulleys, it will be understood, are constantly rotated but in reverse directions, such being possible by reason of them being loosely mounted on the counter-shaft and as are 10 similarly mounted the gears 16 and 17.

Between the smaller gears 16 and 17, there is slidably mounted on the shaft 13, a clutch-collar 20, centrally annularly grooved, as at 22, and having its opposite ends toothed, as 15 at 21, and adapted to engage the teeth of either the gear 16 or 17, in accordance with the direction of movement of the collar.

Pivoted, as at 24, preferably to the front standard of the side-frames, is a bell-crank 20 operating-lever 23, such having at one end an upwardly disposed arm 25, terminating between the small gears 16 and 17, at which point said lever is bifurcated or slotted, as at 26, to engage the annular groove 22 of the sliding collar 20, and thereby adapted to operate the latter in either direction upon the shaft 13. The opposite end of the lever extends at one side of and at the front of the machine and terminates in a convenient 30 handle 27.

Adjacent this handle, the lever 23 is pivoted, as at 28, to the lower end of a vertically moving gravity locking-bar 29, located at one side of the machine and supported in 35 any suitable manner so as to be free to slide, in the present instance, by a keeper 30, attached to the frame of the machine and overlapping the said bar. At its front edge the bar is provided with an angular notch 40 31, with which is adapted to engage the angular shoulder 33, of a gravity latch 34, pivoted as at 35, to the frame in advance of the bar. At the upper end of the bar is located a loose roller 32, the function of 45 which will hereinafter appear.

Carried by the shaft 10, between those bearings 9 that are located upon the sides 1 of the frame, are small gears 36, and supported thereon and meshing therewith are 50 two parallel rack-bars 37, of somewhat greater length than the frame of the machine. That rack-bar at the side at which the gravity locking-bar 29 is located is provided with a trip 37^a, which, when the bars 55 37 move inward to a proper point, as hereinafter explained, will contact with the upper end or tail of the latch 34 and thereby disengage its shoulder from its locking position with the gravity locking-bar and permit 60 the same to fall by its own weight. The same rack-bar also carries upon its upper side and in rear of the locking-bar 29 an inclined cam 37^b, which as it moves forward, will engage under the roller 32

and therefore elevate the locking-bar 29 65 so as to reengage the latch 34 therewith.

Near their rear ends, the rack-bars 37 are provided with bearings 38, for the reception of a journal or shaft 39, upon which is mounted a roller 40, for compressing the 70 sand in the core-plate. When not in operation the compressing-roller 40 is supported upon the extension or table 5.

Immediately in rear of the roller, the rack-bars 37 support the sand-hopper 41. 75 This hopper is formed with a lower reduced discharge-end 42, provided with a sliding cut-off or gate 43. A scraper 44, may be located at the rear side of the discharge 42, the function being to scrape off any surplus 80 of sand as well as distribute the same over the core-plate.

Projecting to one side and forwardly a short distance from the cut-off 43, is a bent rod 45, at the forward end of which is located 85 an L-shaped block 46, the lower extremity of which is slotted and has intermediately pivoted therein, as at 47, a gravity latch 48, the inner end of which, when the latch is raised, is adapted to engage with a 90 notch 49, formed in the adjacent rack-bar 37, thereby locking the rod 45 and the cut-off from movement. An inclined cam 50^a, is located in the path of the tail of the latch and is adapted to elevate the latch into its 95 locking position with the rack-bar at the proper point of the operation of the machine. (See Figs. 4 and 5). A coiled spring 50, has one end attached to the arm 46 of the rod 45, and its opposite end to the 100 adjacent rack-bar 37, the function of the spring being to open the cut-off to permit the flow of sand when the cut-off is not locked by the gravity latch 47.

A striker-bar 52, is pivoted, as at 53, to 105 the rear end of the machine in the path of the cut-off operating rod 45, and is adapted when the hopper has reached the rear end of the core-plate, to contact with said rod and force the cut-off forward to its closed 110 position, thereby preventing waste of sand from the hopper. This striker-bar is preferably yieldingly pressed forward by means of a coiled spring 54.

This completes the description of the construction of the mechanism preferably employed to attain the objects of the invention, it being understood that the same is subject to variations as to details. The operation may be briefly described as follows: 115

Taking the parts in the position in which they are illustrated in Figs. 1 and 6, the handle, 27, is raised, thereby causing the teeth of the sliding-sleeve, 20, to engage the companion teeth of the hub of the small 125 spur-gear, 16, and force the male-member, 18, thereof into frictional engagement with the female-member, 19, of the pulley 14, thus

causing the shaft 10 to rotate in the direction of the arrow. As the rack-bars 37 are carried backward by the rotating gears 36, carried by the shaft 10, the outer end or 5 tail of the gravity latch 48 is raised by reason of it riding up the inclined cam 50^a and hence the inner end of the latch is disengaged from the notch 49 of adjacent rack-bar. The spring 50 then opens the cut-off 10 43 of the sand hopper 41, so that sand is discharged over the core-plate and into the molds, the scraper 44 serving to carry the surplus into the molds, as will be readily apparent. As the rack-bars and hopper 15 move to the rear, the latter is followed by the compression-roller 40, which serves to pack the sand into the molds. By the time the roller 40 has reached the rear end of the core-plate, the cut-off yielding to the influence of the striker-bar 52, which latter 20 has a limited rearward movement, will be closed or moved forward when said cut-off will again become locked by the latch 48 reengaging with the notch 49. At this 25 point—when the hopper is at its rearmost position—the trip 37^a contacts with the upper end or tail of the gravity latch 34, rocking said latch so as to disengage its shoulder 33 from the angular notch 31 of 30 the gravity locking-bar 29, so that the latter will fall by gravity. As this bar drops, the lever 23 is moved in the opposite direction, or, in other words, its handle-end is depressed, so that the sliding-sleeve 20 is 35 moved in an opposite direction, thus releasing the friction-clutch formed between the gear 16 and the pulley 14, and establishing such clutch between the gear 17 and the pulley 15, thereby reversing the direction 40 of rotation of the shaft 10, it being understood that the two pulleys are loose upon the shaft 13 and are continuously driven in opposite directions. This operation will rotate the shaft 10 and its gears 36 in the 45 opposite direction to that described, thus causing the return movement of the rack-bars 37 and returning the sand-hopper and the roller to their initial positions. As the parts return, the roller again operates over 50 the core-plate, and the cam 37^b engaging under the roller 32, reelevates the gravity locking-bar 29 until the notch 31 of the latter is engaged by the latch 34.

This completes the operation of the machine and it only remains to swing the core-plate upwardly upon its hinges, remove the cores, and repeat the operation.

It will be observed that the machine is very simple both in construction and operation 60 and by its use the production of cores is greatly reduced as to cost, in that all manual labor in connection with such production is reduced to a minimum, it simply being necessary to start the machine and

later, at the completion of the operation of 65 the machine, remove the cores from the core-plate.

Having described my invention, what I claim, is:

1. In a core-making machine, the combination with a frame, of a core-plate located thereon, a sand-hopper also located on the frame and adapted to move over the same, a compression-roller mounted on the frame in rear of the hopper, and means for reciprocating the hopper and roller over the core-plate. 70

2. In a core-making machine, the combination with a frame, of a core-plate fixedly supported thereon, a support on the frame 80 on a level with the upper surface of the core-plate, a sand-hopper supported above the frame and adapted to move over the same and the core-plate, a compression-roller connected with and adapted to move in rear of 85 the sand-hopper over the core-plate and supported by the support, and means for reciprocating the sand-hopper and roller.

3. In a core-making machine, the combination with a frame, of a core-plate supported on the latter, a hopper, means for supporting the hopper above and out of contact with said plate and frame, means for reciprocating the hopper over the core-plate, a cut-off at the lower discharge end 90 of the hopper, means for opening the cut-off when the hopper is advanced and directly over the core-plate and for closing the cut-off during as well as subsequent to its return movement, a compressing-means, and means 95 for operating said compressing-means automatically and between the advance and return movements of the hopper. 100

4. In a core-making machine, the combination with a frame, of a core-plate mounted 105 thereon, a movable hopper, means for reciprocating the same over the core-plate, an automatically opening discharge at the lower end of the hopper, means for locking the discharge against opening previous to 110 the advance of the hopper, and means for closing said discharge and locking it against opening at the end of said advance movement.

5. In a core-making machine, the combination with a frame, of a core-plate mounted thereon, a reciprocating hopper provided with a lower discharge-end, a cut-off located in said end, means for reciprocating the hopper, and means for opening the cut-off 115 at the beginning of the advance movement of the hopper and for closing said cut-off at the end of said movement. 120

6. In a core-making machine, the combination with a frame, of a core-plate mounted thereon, a hopper supported above the frame and plate and provided with a lower discharge-end, means for reciprocating the 125

- hopper, a sliding cut-off mounted in the discharge-end of the hopper, a spring for normally opening said cut-off, means for locking the cut-off closed, a trip for disengaging said lock at the beginning of the advance movement of the cut-off, and a striker located in the path of the cut-off for closing the same against the spring at the end of the advance movement of the cut-off.
- 10 7. In a core-making machine, the combination with a frame, of a core-plate mounted thereon, a drive-shaft journaled in the frame, gears carried by the drive-shaft, means for rotating the shaft in reverse directions, opposite parallel rack-bars mounted on the gears, a hopper carried by the rack-bars and adapted to be reciprocated thereby over the core-plate and having a lower discharge-end, a cut-off in said discharge-end, and means for opening the cut-off at the beginning and during the advance movement of the hopper and for closing and locking the same at the end of such movement, during its return movement, and when at rest.
- 15 8. In a core-making machine, the combination with a frame, of a core-plate mounted thereon, a drive-shaft journaled in the frame, opposite gears carried by the drive-shaft, means for rotating the shaft in reverse directions, opposite parallel rack-bars mounted on the gears, a hopper carried by the rear ends of the rack-bars and adapted to be reciprocated thereby over the core-plate and having a lower discharge-end, a cut-off in said discharge-end, means for opening the cut-off at the beginning and during the advance movement of the hopper and for closing and locking the same at the end of such movement, during its return movement, and when at rest, bearings carried by the rack-bars in rear of the hopper, and a roller having its journal in said bearings and supporting the rear ends of the rack-bars on the frame.
- 20 9. In a core-making machine, the combination with a frame, of a core-plate supported thereon, bearings carried by the frame in front of the core-plate, a drive-shaft journaled in the bearings, companion gears carried by the shaft, means for rotating the shaft in opposite directions, opposite rack-bars engaging and operated by the gears, a sand-hopper supported by the rack-bars and having a lower discharge-end, a sliding cut-off in said discharge-end, a bent arm connected to the cut-off and extending to one side of the same, an intermediately pivoted latch carried by the outer end of said arm, a notch in the adjacent rack-bar with which the inner end of the latch is adapted to engage, whereby the cut-off is locked against opening, a spring for normally opening the cut-off when the latch is disengaged from
- 25 the notch, a cam carried by the frame and adapted to disengage the latch from said notch, and a yielding striker-bar connected to the frame in the path of the cut-off and adapted to close the cut-off so that the latch can engage the notch when the hopper has reached the end of its movement.
- 30 10. In a core-making machine, the combination with a frame, a drive-shaft journaled therein, companion gears carried by the drive-shaft, rack-bars supported by the same, a sand-hopper carried by the rack-bars, a core-plate arranged upon the frame below the hopper, drive-gears mounted on the shaft at one side of the companion gears, a counter-shaft, gears loose thereon and in mesh with the drive-gears and provided at one side with clutch-members and at their inner sides toothed, pulleys loosely mounted on the counter-shaft and driven in opposite directions and having clutch-members adapted to coact with those of the gears of said counter-shaft, a sleeve mounted for sliding upon the counter-shaft between the gears thereof and having its opposite end toothed to engage those of either of the gears and provided with an annular groove, a bell-crank lever fulcrumed on the frame and at one end terminating in a bifurcation engaging the annular groove of the sleeve and at its opposite end in a handle, a vertically movable gravity locking-bar located in the frame and having its lower end pivoted to the bell-crank and above the same having an angular notch, a loose roller at the upper end of said bar, a gravity latch pivoted to the frame and adapted to engage the notch of the bar when the bar is elevated, an inclined cam carried by the rack-bar adjacent the said bar and adapted to engage under the loose roller thereof and elevate the bar when the rack-bars are moved toward the front of the machine, whereby the direction of rotation of the drive-shaft of the machine is reversed, and a trip carried by said rack-bar and adapted to disengage the latch from its locking position with said bar.
- 35 11. In a core-making machine, the combination with a frame, of a core-plate supported thereon, a sand-hopper supported above in line but out of contact with the core-plate and provided with a discharge in its lower end communicating with the core-plate, a valve in the discharge of the hopper, means for relatively moving the core-plate and hopper out of alignment with each other, and means for automatically operating the valve in the hopper so as to open the same when the core-plate and hopper align and to close the valve when the core-plate and hopper are out of alignment.
- 40 12. In a core-making machine, the combination with a frame, of a core-plate supported thereon, a sand-hopper supported

above in line with but out of contact with the core-plate and frame and provided with a discharge in its lower end leading to the core-plate, a valve in the discharge of the hopper, means for relatively moving the core-plate and hopper-discharge out of alignment with each other, means for automatically operating the valve in the discharge so as to open the same when the core-plate and hopper aline and to close the valve when the

core-plate and hopper are out of alinement, a compressing means for the sand discharged from the hopper into the core-plate, and means for automatically operating said compressing-means after each discharge of 15 sand from the hopper.

CHRISTOPH J. MICHELS.
